UNITED STATES PATENT OFFICE.

HENRY A. BUDDE, OF MANCHESTER, CONNECTICUT.

DESIGN FOR A CASING FOR REVERSE-GEAR.

46,394.

Specification for Design.

Patented Sept. 15, 1914.

Application filed July 18, 1914. Serial No. 851,831. Term of patent 14 years.

To all whom it may concern:

Be it known that I, HENRY A. BUDDE, a citizen of the United States, residing at Manchester, county of Hartford, and State of Connecticut, have invented a new, original, and ornamental Design for a Casing for Reverse-Gears, of which the following is a specification, reference being had to the accompanying drawing, forming a part thereof, and in which—

Figure 1 is a side elevation, Fig. 2 an end

elevation, and Fig. 3 a top plan view of a casing for reverse gears showing my new design.

I claim:

The ornamental design for casing for reverse gears as shown.

HENRY A. BUDDE.
